HOBBING MACHINE

Homer C. Warner, Cleveland, Ohio, assignor to
 The Lees Bradner Company, Cleveland, Ohio, a
 corporation of Ohio

Application April 1, 1947, Serial No. 738,647

3 Claims. (Cl. 90—4)

1

My invention relates to hobbing machines and relates more particularly to a novel and advantageous driving mechanism for the operative elements thereof which may be readily and simply so set up as to adapt said machines for the precisely controlled hobbing generation of helical gears or the like, which are thereby caused to respond to prescribed specifications.

Hobbing machines heretofore have been provided with transmission gearing wherein a lead differential gear set is employed to vary the speed of rotation of the work spindle according to the rate of relative feed movement of the hob and work blank spindles to effect cutting of gear teeth having a desired helical lead.

Similar lead differential gearing has commonly been interposed between the index gearing and the work spindle, but such arrangements have been subject to the objections of requiring burdensome time-consuming calculations in order to determine the required gear ratio between driving and driven lead and other gears to condition the transmission of the machine for effecting cutting of the desired number of gear teeth having the desired lead, and again after a first gear of a set of mating gears has been then cut, it is repeatedly necessary to repeat the calculations in order to condition said transmission for the cutting for each relatively mating gear having different numbers of teeth.

Moreover, as a result of such calculations, those skilled in the art and familiar with these present day machines can only decide upon a ratio between said lead gears that merely approximates the required lead for the gear to be cut. Therefore, to cut a gear blank to produce a gear adapted to mate with a given helical gear, the ultimate result is too largely dependent upon the skill or possibly good luck of the calculator.

In the mechanism of my invention, I designedly place the lead differential gearing in advance of the index gears, and by virtue thereof, I have found it possible to greatly reduce the otherwise required calculations and much of the mechanical changes in the mechanism set-up, for effecting the hobbing of a helical gear according to required specifications, and thereafter, to greatly simplify and reduce the set-up work for producing sets of relatively mating gears having relatively different numbers of teeth, including elimination of the ordinarily required calculations.

An object of my invention therefore is to afford greater simplicity in the nature of the pre-

2

liminary set-up of a hobbing machine to adapt it for the cutting of helical gears of desired specifications.

Another object of the present invention is therefore to provide a mechanism of the foregoing character which is readily set up for the hobbing of helical gears without requiring time-consuming calculations.

Another object of my invention is to provide a novel and improved arrangement of driving elements of a hobbing machine whereby the same may be successively expeditiously and properly set up for the generation of helical gear teeth of widely different specifications.

Another object of my invention is to substantially reduce and/or avoid the previously required time previously spent in working out laborious calculations and/or making reference to various pre-prepared charts, incidental to the setting up of a hobbing machine in such manner that the rotational rate of the blank will be so relatively timed relative to the hob and work blank feed movement in a direction parallel to the axis of the work blank whereby any helical gear having teeth having a prescribed lead angle may be accurately cut by the hobbing machine.

Another object of my invention is to reduce and simplify calculation and set-up work for hobbing relatively mating gears to cause them to have prescribed different numbers of teeth.

Another object of my invention is to achieve setting up of the transmission mechanism for a hobbing machine to condition said machine for the cutting of helical gears responding to prescribed numbers of teeth and/or lead of said teeth by an improved method.

Other objects of my invention and the invention itself will become clear to those skilled in the art by reference to the drawings hereof which illustrate a transmission mechanism for hobbing machines which is a preferred embodiment of my invention, and by reference to the specification related to the said drawings whereof:

45 Fig. 1 is a schematic diagram of the mechanism of my invention applicable to a hobbing machine;

Fig. 2 is a transverse sectional view taken in a plane intersecting the axes of a hob drive gear and work spindle;

50 Fig. 3 is a sectional view of a lead differential gear mechanism taken in the plane of the input and output relative drive and driven shafts thereof;

55 Fig. 4 is a view taken transversely of the work spindle showing a pair of helical mating power

output gears comprising a driving helical gear secured to the work spindle, the view also comprising a relatively parallel section taken through a driving power input worm and a fragment of a relatively driven gear secured to said spindle;

Figs. 5 and 6 are, respectively, elevational views of a hobbing machine, the first showing an end elevational view of the lead gears of the mechanism in side elevational view, and the second showing the index change gearing, the feed change gearing thereof in side elevational view;

Fig. 7 is a schematic perspective view of a portion of the lead differential mechanism of Fig. 3;

Figs. 8 and 9 are views illustrating an assembly of transmission mechanism comprising a rapid traverse differential gear unit and lead screw and differential gearing driving means, Fig. 8 being a perspective view of some of the parts shown in Fig. 9 which is largely a diametrical section of the apparatus of Fig. 8 and affording a showing of certain power drive elements related to the apparatus of Fig. 8;

Fig. 10 is a view of the rapid traverse mechanism largely taken on a diametrical line of section of the driving and brake mechanism thereof; and

Fig. 11 is a view of gearing associated with a pair of shafts, said gearing being shown in diametrical section with the shafts shown in side elevation.

Referring now to the various figures of drawings, in all of which like parts are designated by like reference characters, the said drawings are illustrative of a transmission mechanism which is a preferred embodiment of my invention, said mechanism being adapted to cause the hob and work spindles of a hobbing machine to be rotated at suitable rotational rates, and to cause a relative feeding movement between the spindles in a direction parallel to the spindle axis, whereby said machine may be adapted for the hobbing of helical gears having prescribed specifications, particularly with reference to the number of teeth and the lead of said teeth of any helical gear to be cut.

Certain of the drawings show the said mechanism as applied to a hobbing machine wherein the relative feeding movement between the spindles is of the nature of that disclosed in the prior patent to H. C. Warner et al. No. 2,075,489, dated March 30, 1937, wherein the feed movement is imparted to the head carrying the hob, but it will be apparent to those skilled in the art to which my invention appertains that my invention is readily applicable to hobbing machines wherein the feed movement is imparted to the work spindle, and in fact, to all hobbing machines wherein there is imparted to either or both hob and work spindles a relatively feeding movement in parallelism to the axis of the work blank.

Referring primarily to the diagram of Fig. 1 with explanatory reference to the other drawings, the transmission mechanism disclosed therein is a preferred embodiment of my invention.

The said illustrated embodiment of my invention, is here disclosed as being applied to a vertical type differential hobbing machine, of either single spindle or multiple spindle rotary types.

While the mechanical drawings of Figs. 2-10 are more particularly relied upon to show details of preferred mechanical construction relating to the transmission mechanism of my invention, certain of said drawings sufficiently show the same as applied to well known elements of a typical vertical type hobbing machine, that the op-

eration and operative results of said mechanism of my invention will be readily understood.

Although it will be understood that hobbing machines, of the type referred to, commonly are provided with a suitable preliminary adjustment mechanism whereby the hob spindle 88 may, by a rapid traverse movement initially bring the hob spindle into full depth "in" position with respect to a work blank carried by a work spindle S, and whereby subsequently, the hob spindle may be withdrawn to the restored or "out" position, the hob spindle being usually movable in a substantially rectilinear path, preferably by electrical power means, in any usual manner, the present drawings do not essay to show all such mechanical details of such ancillary mechanism nor the electrical controlling means therefor which may be of any well known type, the present invention being related only to the mechanism for effecting operative relative feed movements of said hob and work spindles, and to the preliminary "set-up" of said mechanism to cause the hob to so cut gear blanks as to generate helical gears of prescribed specifications.

The sequence of movements of the hob head when the hobbing mechanism is set up to hob a gear comprises first an actuation of the rapid traverse motor 60, including actuation of the lead screw 15, to effect quick return of the hob slide to the starting position, then with the rapid traverse motor T shut off and its shaft braked by a brake 61-61a, the main drive motor and the "in-out" motor (not shown) is started whereby the feed is engaged and the hob OH is brought into the proper depth, whereupon the "in-out" motor is stopped and its shaft likewise then automatically braked, but the main transmission driving motor M which was preferably started at the same time continues to run to drive the transmission mechanism disclosed herein, including the lead screw 15, to feed the rotating hob across the face of the rotating work blank, which is thereby operated upon.

When the machine is arranged with a standard "in-out" mechanism, suitable adjustable stops of well known character are adjustably set, one of such stops adapted to cause the hob to be brought into full depth position with just sufficient clearance so that the hob OH will not engage the work blank when in the full depth position, and another stop should be adjustably set so that it will be actuated as soon as generation of the gear teeth on the blank has been completed to effect restoration of the hob to a normal inoperative position to permit reloading of the work spindle S with a new blank.

Portions of horizontal slideways carried by the hob head carriage H-H upon which the mount 55 for the hob head 50 is adapted to slide horizontally, are shown at 61', and portions of a pair of vertical guides for the carriage H-H which supports the hob head 50, are shown at 62'.

The carriage H-H is movable only in vertical directions by virtue of timed rotational movement given a lead screw 15 which is anchored at its lower driven end to a stationary portion of the mechanism frame K, Fig. 2, to prevent longitudinal movements of the screw, the threaded upper end being meshed with an internally threaded bore of an element of said carriage, which is thus moved vertically responsive to rotational movement of the screw.

The carriage being movable vertically on slide-ways 62 and the hob head 50 being movable

horizontally on slideways 61 of said carriage; to accommodate such movements the hob drive shaft 30 comprises upper and lower relatively interlocked and relatively reciprocable splined upper and lower vertical sections to permit up and down movement of the carriage; similarly, the horizontal shaft 31 likewise comprises relatively longitudinally extensible relatively splined sections to permit continuous driving of the hob spindle by a gear 6 secured to the upper section of the shaft 30 through the relatively meshed gear 5, in turn affixed to the laterally immovable section of the shaft 31, said spindle being carried by and movable with the hob head, during lateral "in-out" adjustment movements of said hob head.

The hob head 50 carrying the spindle 88 is also carried by a rotatably adjustable support whereby the hob may manually be preadjusted to dispose its axis at the proper angle relative to the vertical axis of the work spindle S in order to set the helically arranged series of hob teeth at the proper operating angle to the work blank spindle S.

The section of the shaft 31 which is laterally movable with the head 50, together with the relatively meshed gears 3-4, as well as the relatively meshed gears 2 and 1 are all fixedly journaled in the hob head whereas the relatively meshed gears 5 and 6, together with the driving section of the splined shaft 31 are all journaled on the solely vertically movable carriage H-H as distinguished from the laterally movable carriage-supported hob head 50.

With the foregoing explanation of common generally known portions of a vertical hobbing machine, the diagram of Fig. 1 sufficiently discloses my improved transmission mechanism in a preferred embodiment, and its application to such vertical type hobbing machine is shown in Figs. 5 and 6.

Referring now more particularly to Fig. 1 but with accompanying reference to the other drawings, for a description of the operative elements of my improved transmission mechanism and to show their cooperative relationship, the work and hob spindles S and 88 are both shown as rotatably driven from a main drive shaft 32, which, during operation of the hobbing machine, is driven by a motor M, the pulleys N and P, and belt 64, or in any other suitable manner at any desirable rotational speed.

While herein, the shaft 32 is conveniently designated as the main drive shaft, it will be understood that the shaft 30 or other primary driving shaft or shafts may, in other embodiments, be more properly termed the main drive shaft; Fig. 1 shows an alternative arrangement where a motor M' is adapted to drive the shaft 30 in any suitable way, thus replacing the motor M, the broken-away portion of the shaft 30 as designated at R, being here intended to indicate that in the present portion of the description the motor M rather than the motor M' is the driving motor.

The shaft 32 through an affixed gear 8, and mating gear 7 secured to the shaft 30 which through the relatively meshed gears 6 and 5 drives the shaft 31, and, in turn, the shaft 31, through successive pairs of meshed gears 4-3 and 2-1, drives the hob spindle H, at a rate determined by the rotational speed of the motor and the driving ratio of said pairs of meshed gears.

The shaft 32, to which is secured the gears 8 and 33, at its two ends, drives a differential in-

put shaft 35 through the gear pair 33-34. To the ends of said input shaft 35 are secured the gear 34 and a differential driving gear 36 of the differential mechanism L which is provided with a differential driven gear 37 which is disposed in axial alignment with said gear 36, and is secured to a differential output shaft 23, which drives the set of index change gears A-B-C, the driving index gear A being also secured to the shaft 23.

The driving and driven gears 36 and 37 are axially interspaced in a differential casing 22, to which a worm wheel 20 is rigidly affixed, and one or more pairs of relatively intermeshed differential pinions 40 and 41, each separately journaled on shafts secured to the casing 22, are adapted to communicate driving motion from the gear 36 to the gear 37, each of the pinions 40 being meshed with the gear 36, and each of the pinions 41 being intermeshed both with the pinion 40 and the gear 37.

The set of index gears may be variously arranged, but in the form shown in Fig. 6 comprises a driving gear A secured to the differential output shaft 23 and a driven gear C, there being one or more intermediate index gears B interposed between and in serial relation with the gears A and C whereby the gear C is driven by the gear A through the intermediate gears B.

The output index gear C is secured to a shaft 43 to whose other end a worm pinion 9 is affixed, said worm pinion being meshed with a worm wheel 10 rigidly secured to the work spindle S whereby the spindle may be rotated at an appropriate rotational rate by the worm pinion 9. The spindle S being rotated, a helical gear 11 affixed to the spindle S drives a relatively meshed mating helical gear 12 which, being affixed to a shaft 44, rotates said shaft to whose other end the driving feed gear D of feed gears D-E-F is secured, reference being here made to the right hand side of Fig. 6 for a showing of an appropriate set of said feed gears, the gear F being the driven gear and the gear E, in any appropriate number, transmitting driving motion to the output feed gear F.

The output feed gear F is secured to a shaft 45, the other end of which having affixed thereto the driving gear 49 of a rapid traverse differential mechanism T comprising a frame 46 to which is secured a worm gear 48 which, during cutting feed movements of the hob, is maintained non-rotatable in a manner later described.

Rotary motion is communicated from the input gear 49 to the differential driven gear 70 through one or more pairs of differential pinions, each pair comprising relatively intermeshed pinions 53 and 54 which, in turn, are respectively meshed with the gear 49 and 70. Each of the differential pinions 53 and 54 are separately journaled on shafts such as 91 anchored to the differential casing 46 and preferably the driving ratio between the gears 53 and 54 is a 1 to 1 ratio. The driven gear 70 is secured on the end of a shaft 63 51 to which is also affixed a bevelled gear 17 and a worm pinion 13, said gear and pinion, as also the worm gear 48, being respectively longitudinally interspaced along the shaft 51.

Rotational movement imparted to the shaft 51 communicated to the worm pinion 13 causes said pinion to drive the worm gear 14 which is rigidly affixed to the lower end of the lead screw 15 whereby the lead screw 15 is given a rotary movement to vertically move the hob carriage to cause the required feed movement of the hob spindle 88.

while moving transversely across the periphery of the work blank placed on the work spindle S, and in a direction parallel to the axis of said work spindle.

It will be apparent that the bevelled gear 17 secured to and rotated with the shaft 51 at all times rotates in a definitely timed relation with respect to the driven lead screw 15 and therefore is effective to communicate a compensatory rotational movement to the element 22 of the lead differential mechanism L, which is proportional to the rate of feed movement of the carriage H—H and therefore of the hob OH.

The worm gear 20 secured to the hub of the differential frame 22 is driven by the relatively meshed worm 21 secured to a shaft 64, to the other end of which the gear 19 is affixed and is, in turn, driven through an idler gear 89 by a gear 18 secured to a shaft 63, to the other end of which a lead gear G is affixed. The gear G is adapted to be driven through one or more idler gears H by a gear J secured to one end of a shaft 62 which carries a bevelled gear 16, in mesh with, and driven by the bevelled gear 17, which is secured to the aforesaid shaft 51.

In the exemplary operations hereinafter set forth, the set of gears 18—89—19 when having a 1 to 1 ratio are relatively unimportant since the shaft 63 could be substituted for the shaft 64 as a carrier for the worm 21, and are only shown since they have been incorporated, as a matter of convenience, in a Lees-Bradner type of hobbing machine.

Similarly, the gears 33—34 could similarly and for like reason be omitted, these being preferably of a 1 to 1 ratio and the shaft 32 could be extended to include the input shaft element 35 of the differential mechanism L. It will be noted that the differential mechanism L and T are quite similar, the latter being merely employed to effect a rapid vertical traverse movement of the hob OH, achieved by a rapid rotation of the lead screw 15, at times prior to and subsequent to a gear teeth generating feed movement of the hob.

Having described the operation of the transmission mechanism of my invention with omission of specific description relating to the rapid traverse mechanism, reference will now be had to various of the figures of drawing showing typical arrangements of the index gearing, the feed gearing, the lead gears and the differential mechanisms L and T, and also showing other of the parts referred to in the foregoing narrative.

The differential mechanisms L and T are quite similar in construction and Fig. 7 is therefore applicable to both said mechanisms, being a schematic view of driving and driven axially aligned gears, such as the gears 36 and 37 of the mechanism L and the differential pinions, one pair of which are shown at 40 and 41, the latter being relatively intermeshed and respectively meshed with said gears 36 and 37, the relatively supporting pinion shafts indicated at 40' and 41' being anchored in the manner schematically shown in Fig. 1 as in the frame 22 of the mechanism L.

Figs. 8 and 9 which illustrate the differential mechanism T, also afford a showing of the like construction employed in the mechanism L. The rotatable frame 22 of mechanism L corresponds to that shown at 46 in Figs. 8 and 9, and the shaft 51 is shown as having secured thereto in longitudinally spaced relation the bevelled gear 17 and worm pinion 13, above referred to, and the shaft

45 is shown as provided with a gear spindle 45' to which is secured the output feed gear F.

The mounting of the differential spindles, such as those at 40' and 41' on the differential frame 22, is relied upon to communicate the increment of speed variation to be imparted to the gear 37 and the shaft 23 by the effect of rotation of the worm pinion 21 by motion derived from the shaft 51, as described, since the rotational rate imparted to the gear 37 is at a rate which is the algebraic sum of the rotational rate of the input gear 36 plus the rotational rate imparted by the worm 21 to the frame 22.

The action is similar with respect to the acceleration of rate of rotation imparted to the shaft 51 carrying the gear 70 by rotation of the frame 46 of the differential mechanism T by the driving effect of the worm 55 on the gear 48.

Fig. 5 illustrates the lead gears G—H—J, the intermediate lead gear H being interposed between and meshed with said gears G and J. It may be said that the gearing illustrated in Figs. 5 and 6 is in forms which are typical in change gearing commonly employed in hobbing machines and other forms of change gearing may be substituted for the forms herein shown by the drawings which merely illustrate my present preference in this respect as to the form of change gearing which may be conveniently employed in the Lees-Bradner machine in which my invention is shown as embodied.

It may be here stated as is obvious that the diagrammatic view of Fig. 1 illustrates parts in variously differing spaced relationship and to different scales than actually are employed in the mechanism of my invention, and for a proper understanding of relative sizes of parts shown on different of the drawings reference should be had to the mechanical drawings of Figs. 2-11 inclusive and as these may be modified by this specification and particularly by the gear ratios set forth elsewhere herein.

Brief reference is now made to certain of the mechanical drawings, of which Fig. 5 illustrates the set of lead gears G—H—J which are disposed in an outwardly facing compartment L—C of a housing forming part of the stationary frame of the hobbing machine, the cover plate for said housing having been removed to thereby expose to view said lead gears.

It may be said that the terminal lead gears G and J are preferably on fixed centers whereas the intermediate gear H is adapted for lateral adjustment to vary the radial distance between the axis of the gear H and the axes of the gears G and J according to variations in the sizes of gears G and J and sometimes possibly of the gear or gears H, as may be desired, and to meet the requirements of practice.

Fig. 6 similarly shows from left to right a set of index gears and a set of feed gears, the arrangement being similar in each case and each set of said gears comprises a pair of intermediate relatively intermeshed gears respectively shown at B and E. These intermediate gears may in practice be but a single gear or any convenient plurality of gears, the essential requirement being to secure necessary gear ratios as between the terminal index gears A and C and the terminal feed gears D and F.

Figs. 5 and 6 also show the essential elements of the hob carriage H—H, the hob head 50 and the hob spindle 88, the latter carrying a hob, in the usual manner.

Fig. 10 illustrates the driving elements of the

rapid traverse mechanism comprising motor 60 having a double ended shaft 59 to which at one end a brake drum 61a is affixed and disposed in operative relation to brake shoe devices, the latter normally holding the drum 61a and the motor shaft 59 immovable.

Automatically operable means, indicated at 61, of a well known type, are adapted to retract the brake shoes to release the brake concurrently with the starting of the motor 60. To the other end of the shaft 59, a bevelled gear 58 is affixed, being meshed with a second bevelled gear 57 secured to a shaft 56 to which is secured a worm pinion 55 meshing with the worm gear 48 which, in turn, as best shown in Figs. 1 and 9, is secured to the hub 46' of the frame 46 of the differential mechanism.

As previously stated, the rapid traverse mechanism is, during hob cutting operations, inoperative and therefore the brake comprising the drums 61a and the brake shoes 61 maintains the differential frame 46 non-rotatable by the locking effect of the non-reversible worm gearing 48-55.

Whenever, during the operation of the hobbing machine, the rapid traverse mechanism is operative, it is adapted to speed up the rotational rate of the shaft 51 and thereby the lead screw 15 by the driving effect of the relatively rapidly rotating worm 55 on the worm gear 48 added rotational speed is effected regardless of any concurrent rotary movement imparted to the differential gear 49 by the feed gear F.

By virtue of that feature of my invention whereby the disposition of the lead differential mechanism L in advance of the index gearing A-B-C whereby the index gearing is driven through the differential mechanism L at all times, I achieve the resulting simplification of the preliminary set up for the transmission gearing for the cutting of helical gears having prescribed specifications which are fully apparent from this specification and made quite clear by reference to the typical setup, as set forth under the headings Index gears, Feed gears and Lead gears, and as demonstrated by the typical examples following the subject matter under the said headings.

To ensure a ready and complete understanding of my invention, a typical setup for the hobbing of helical gears comprising typical practical driving ratios for the index change gearing, the feed change gearing, and the lead change gearing, are now set forth together with one practical typical value of the lead screw pitch whereby advantages in readily ascertaining and effecting the correct set up for hobbing helical gears of varying specifications may be achieved.

Index gears

The ratio of the serially related gear sets 1-2, 3-4, 5-6, 7-8, 33-34, 36-37, and that comprising the worm and wheel 9-10 determines the index constant, and therefore the number of teeth which the hob will cut on the peripheral surface of the work blank carried by the spindle S.

Assuming a 1 to 1 ratio for the index gears A-C, and that the driving ratio of gears 1 to 2 and 3 to 4 were 6 to 1, that of gears 5-6 and 7-8 and 33-34, 36-37 were 1 to 1, and that the driving ratio between the worm 9 and the gear 10 which is secured to the work spindle S, is 54 to 1, then, upon operation of the machine, it is obvious that the hob OH will cut 9 teeth on the blank carried by the work spindle S.

The index gear formula could then be set forth as

$$\frac{A}{C} = \frac{9}{N}$$

where N is the number of teeth which the operator desires to have cut on the periphery of the work blank, the ratio of A/C being the driving ratio of the index gears comprising the gears A and C.

Feed gears

The ratio of the serially related gear sets 11-12, 13-14, 49-50, and the pitch of the lead screw 15 determines the travel or feed of the hob for each single rotation of the work spindle S which carries the work blank.

Therefore, assuming a 1 to 1 driving ratio as between the feed gears D and F, a ratio between the gear 11 which is secured to the work spindle, to gear 12, of 3 to 2, and that the ratio between the gears 13 and 14 is 2 to 15, and with the pitch of the feeding lead screw 15 being one-half inch, then, in such a case, a 1 to 1 driving ratio of gears F and D will achieve a decimal expressed hob feed of .100" for each complete rotation of the work spindle S, and of the work blank rotating therewith.

Thus, by providing a gear at F, having 100 teeth, the set-up operator may readily predetermine that the hob feed shall be equal to any multiple of .001" which may be required, by merely substituting a gear D having such a number of teeth as will correspond in number to the number of thousandths (of an inch), of hob feeding movement required.

The determination of the setup for achieving a desired feed movement of the hob OH, is thus determinable without calculations or reference to charts, and with the exercise of little mathematical skill.

Lead gearing

The pitch of the screw 15 as well as the respective ratios of the gear sets 13-14, 16-17, G-J, 18-19, 20-21, the ratio between the differential gear casing 22 to the shaft 23, and ratio of gear sets A-C and 9-10, is determinative of the amount of hob advance for each single rotation of the work and therefore determines the lead of the gear teeth formed in the blank by cutting action of the hob teeth.

For example, in a typical and practical set up, and assuming the aforesaid pitch of lead screw pitch being equal to $\frac{1}{2}$ ", let the following gear ratios be assumed as existing in the above gear sets, whose ratios have not above been set forth, to wit:

Ratio of gearing 13-14 being 2 to 15, that of 16-17 being 5 to 8, that of 18-19 being 1 to 1, that of 20-21 being 8 to 1, and that of 22-23 being 2 to 1.

Then, also assuming, as aforesaid, that the ratio of

$$\frac{A}{C} \text{ equals } \frac{9}{N}$$

(see under "Index gears"), and that the ratio of the gear set 9-10 equals 1 to 54, then for each single rotation of the work spindle and work blank, the lead expressed in inches is equal to the product of N multiplied by G, divided by J, or $N \times G/J$.

This value, expressed in terms of inches of lead, is found as the product obtained by multiplying the following series of fractions ascer-

11

tainable from the above and foregoing listed ratio values, as follows:

$$\frac{54}{1}, \frac{N}{9}, \frac{1}{2}, \frac{8}{1}, \frac{1}{1}, \frac{5}{8}, \frac{2}{15}, \frac{1}{2}$$

the result being expressed in inches, and being multiplied by the ratio G/J for the gear set G—J, an ultimate product of

$$N \times \frac{G}{J}$$

which being reduced to numerical values, expresses the lead value in inches, therefore the equation G:J::lead:N expresses the relationship which is controlling.

It is to be noted therefore that the driving ratio of lead change gears G and J, is thus made equal to the lead for each tooth of the gear to be cut and from the foregoing, it is apparent that having first calculated the ratio of the gear set comprising gears G and J, these same change gears G and J are used without any substitution of either, when the hobbing machine is subsequently employed to cut any and all gears which are relatively mating with a first helical gear for which the gear ratio G/J has been ascertained. The above advantage is achieved as a result of the positioning of the set of lead differential gears between the hob drive and the index change gears.

When cutting all other mating helical gears, it is therefore only necessary to employ the predetermined gears G and J and then, as previously related, to so choose the index driven gear C that such a gear C will have the proper number of teeth in the helical gears to suit the number of teeth in the helical gears to be cut.

The following typical examples will show the practical application of the above described methods, the first being for a specified helical gear, and the second being for a relatively mating helical gear having a different number of teeth whose lead value is also different.

The above result is achieved in the mechanism described while still permitting changing of the feed drive gear D at any time to vary the amount of speed required for cutting blanks of different materials.

For the first example, and while retaining the aforesaid assumed values of gear ratios, for hobbing a helical gear having 20 teeth having a lead of 32":

$$\text{Index gears, } \frac{A}{C} = \frac{9}{N} = \frac{9}{20} \text{ or } \frac{36}{80}$$

Therefore, gear A should be provided with 36 teeth, and the gear C should be provided with 80 teeth.

$$\text{Lead gears, } \frac{G}{J} = \frac{\text{lead}}{N} = \frac{32}{20} \text{ or } \frac{64}{40}$$

Therefore, the gear G should have 64 teeth and the gear J should have 40 teeth.

To then cut a relatively mating helical gear having 25 teeth and 40" lead:

$$\text{Index gears, } \frac{A}{C} = \frac{9}{N} = \frac{9}{25} \text{ or } \frac{36}{100}$$

whereby gear A may remain unchanged, with 36 teeth and a gear with 100 teeth is substituted for the gear C.

$$\text{Lead gears, } \frac{G}{J} = \frac{\text{lead}}{N} = \frac{40}{25} = \frac{8}{5} \text{ or } \frac{64}{40}$$

and the gears G and J, having 64 and 40 teeth, respectively, will be left in place for the cutting

12

of the above and all relatively mating gears, with respect to the helical gear for which the setup of the above first example was employed.

The above simple calculation clearly shows that for cutting mating helical gears, it is only necessary to substitute for the previous index gear C having 80 teeth, an index gear C having 25 teeth, in order to cut the desired helical gear having a different number of teeth, 25 instead of 20, and a different lead value of 40" instead of 32".

Therefore, for all relatively mating helical gears, the lead is always in direct proportion to the respective numbers of teeth in such mating gears, the only change necessary to cut any such mating helical gear being to provide an index gear C whose number of teeth corresponds to the number of teeth desired in the mating helical gear, and in such case, it is unnecessary to alter the originally employed lead gear ratio of the first example, which is maintained constant for the hobbing of all relatively mating gears.

The simplified set-up of the mechanism for the cutting of helical gears is to be distinguished from the nature of set-up required in prior differential hobbing machine transmissions wherein the position of the index gears is in advance of the position of the lead differential in the line of drive from the point of the power takeoff for driving the hob which leads to the driving worm for the work spindle, and wherein the rates of rotation of said index gears would be unaffected by the imposition of the increment of driving motion variation communicated to the lead differential element corresponding to the differential casing element 22, by any means such as the present worm gearing 21—20.

With such a prior arrangement, it would be necessary, when cutting helical gears having different numbers of teeth, to first change the index gear C, and also to change the lead gears G—J, and in such case, changing the index gears for the number of teeth being cut, does not automatically effect any change in the value of lead as in my improved mechanism, as shown by the above recited examples.

It will be noted that with my improved mechanism, the lead gears J—G are the same for all mating helical gears being cut, which makes for accurate matching of leads.

In the above described prior art arrangement of differential mechanism and index gearing, the lead gears J—G must be different for helical gears having different numbers of teeth, and as a result, two sets of calculations are required. In calculating these gears, the best that can usually be done, by those skilled in the art, is to find gear ratios that approximate the leads required. Therefore, the approximate matching of leads in such cases, is dependent upon the skill, or possibly good luck of the calculator.

From the foregoing, it will be clear to those skilled in the art that my invention is in like manner as readily applicable to hobbing machines wherein relative hob and work blank traversing motion in a direction parallel to the work spindle is effected by longitudinal movement of the work spindle instead of by the aforesaid herein described relatively parallel movement of the hob, and in any such application, the only difference from the embodiment of my invention herein described resides in the different arrangement of the machine whereby, for instance, the feed lead screw 15 is adapted to communicate a longitudinal feeding movement to the work spindle, while the rotating hob spindle is rela-

tively stationary in properly adjusted "depth" position.

It will be understood that rotary motion at a rate proportional to the rate of relative hob and work spindle relative feed movement to compensatorily rotate the frame 22 of the differential mechanism L may be derived otherwise than from the shaft 51 through such means as the relatively meshed gears 16 and 17 and, for instance, rotation of the shaft 62 may be afforded by meshing the teeth of a gear secured to said shaft with the teeth of a rack carried by the hob carriage or other movable element which is movable at a rate which is proportional to the rate of said relative feed movement or where, as in known prior constructions, other means than that involving the differential mechanism T, herein shown, are employed to achieve rapid traverse movement between the hob and work spindles, and the operative drive between the feed gear F and the shaft 51 is substantially inflexible, then the drive to such a shaft as indicated herein at 62 might be taken from the feed gear F or from any other element of the drive wherein suitable provision is made to ensure that the shaft 62 may be driven at a rate proportional to the rate of relative feed movement as between the hob and work spindles.

The differential mechanism T affords an advantage over prior constructions which commonly involve the necessity of operating clutches between the gear F and the feed mechanism comprising any element equivalent to the feed screw 15 in order to drive such feed mechanism at a relatively rapid rate.

The present transmission mechanism affords a means of ensuring that all relative feeding or opposite retracting movements as between the hob and work spindles may be effected while still ensuring that the hob teeth are moved in such manner with respect to the helical teeth previously cut on the gear blank will not cause damage to said gear teeth. In other words, said hob teeth during such traversing movement will track in the helical cut of the work blank previously generated, assuming, of course, that the transmission mechanism is still operative by power delivered to the power input shaft 32.

Again, while the transmission mechanism of my invention is being driven should the portion of the shaft 51, which is disposed between the gear 17 and the differential mechanism T be taken away and a hand crank applied to the portion thereof remaining which carries the gear 17 and the worm 13, turning of said remaining portion of the shaft 51 to achieve feeding movements of the hob carriage H—H by rotation of the screw 15 at any desired rate of crank turning will be sufficient to afford correct operational movements of the hob and work spindles, the compensating drive through the lead gears to turn the lead differential frame 22 in any such case being operative to effect proper relative feed movements of the work and hob spindles.

Although, I have herein emphasized the advantages accruing through the positioning of the differential mechanism L in the transmission mechanism of my invention, attention is directed to the fact that I believe the method of and apparatus for communicating the rapid traverse movement from a rapid traverse motor as 60 to such means as the shaft 51 to also be novel and to involve invention.

Having above described the apparatus involving transmission mechanism in a particular

embodiment, I am aware that the said invention may be embodied in widely varying embodiments and that my invention may be applied to hobbing machines of varying constructions from that herein shown and described, and that the specific construction of the various instrumentalities such as the differential mechanisms L and T may be also widely varied and may be replaced by equivalent structures adapted for the intended herein described purposes.

I claim:

1. In a differential type hobbing machine of the type adapted for the generation of helical gear teeth the combination with motor means, of a work spindle, a hob spindle and means for relatively feeding one of said spindles with respect to the other in a direction parallel to the axis of the work spindle, and a pair of relatively parallel drives from said motor means, each for respectively transmitting power for rotating a different one of said spindles, each at a rate which is in relatively timed relation to the rate of rotation of the other, said work spindle and said feeding means being driven responsive to rotary movement transmitted over a first of said drives to said work spindle, a lead differential mechanism and a set of index gears serially so disposed in said first drive that said index gearing is driven by rotary movement communicated thereto by said mechanism, and said work spindle and said feeding means are each rotated by rotary movement delivered to each from said index gearing, said mechanism comprising a pair of relatively driving and driven gears and rotatable means adapted when rotated to vary the rotational rate of said driven gear by an amount equal to the algebraic sum of the rotational rates of said driving gear and of said rotatable means and transmission means for communicating rotary movement to said rotatable means, said transmission means being actuated by an element of the drive for effecting said spindle feed movement, and a set of lead gears serially interposed in the line of drive including said transmission means and said rotatable means.

2. In a differential type hobbing machine of the type adapted for the generation of helical gear teeth the combination with common motor means for transmitting rotary motion over relatively branched drives of a work spindle and a hob spindle respectively driven by rotary movement communicated from said motor means over a different one of said drives, feeding means actuatable by rotary motion transmitted over the work spindle drive and adapted to effect feed movement to one of said spindles with respect to the other in a direction parallel to the axis of the work spindle, lead differential gearing and a set of index gears so relatively serially disposed in said work spindle drive in advance of said work spindle as to dispose said lead differential gearing in advance of said index gears, and whereby the output gear of said index gears is adapted to transmit rotary motion to said work spindle and to said feeding means, a set of feed change gears interposed in the line of drive between said index output gear and said feeding means, said differential gearing comprising a pair of relatively driving and driven gears and rotatable means adapted when rotated to vary the rotational rate of said driven gear by an amount equal to the algebraic sum of the rotational rates of said driving gear and of said rotatable means, and transmission means for communicating rotary movement from said output feed gear to said ro-

tatable means, and a set of lead change gears interposed in said transmission means, the output one of said feed gears having 100 teeth, and the driving ratio of said feed gears being equal to the quotient obtained by dividing the number of teeth in the input feed gear by the number of teeth in the output gear thereof, and the rotational driving ratio of said motor means and the gearing ratios and the rate of relative feed movement between said spindles in the line of drive to said work spindle and to said feeding means including said feed gears being such as to drive said feeding means at a rate of $\frac{1}{15}$ inch (.0100") for each complete rotation of said work spindle, when the input and output feed gear rotational rates are equal, whereby the provision of an input feed change gear having any lesser number of teeth than 100 teeth is adapted to effect a rate of drive for said feeding means equal to one hundred thousandths of an inch (.001") multiplied by the above quotient, expressed in thousandths of an inch.

3. A hobbing machine of the type adapted for the generation of helical gear teeth, the combination with driving motor means, a work and a hob spindle, feed means comprising a rotary driving element for communicating a relative feed movement between said spindles in a direction parallel to the axis of the work spindle, and a pair of transmission drives in relatively parallel relation both receiving power from said means adapted to rotate said spindles in relatively timed relation, a lead differential gear mechanism, a set of index change gears, and work spindle driving gearing in respectively successive driving relation in a first of said drives, and hob spindle driving gearing disposed in a second of said drives, a set of feed change gears, means
